UNITED STATES PATENT OFFICE.

THOMAS F. BUDGE, OF MALAD CITY, IDAHO.

CLOTHES-PIN.

1,194,597.

Specification of Letters Patent. Patented Aug. 15, 1916.

Application filed October 18, 1913. Serial No. 795,982.

To all whom it may concern:

Be it known that I, THOMAS F. BUDGE, a citizen of the United States, residing at Malad City, in the county of Oneida and State of Idaho, have invented certain new and useful Improvements in Clothes-Pins, of which the following is a specification.

This invention relates to new and useful improvements in clothes-pins and particularly to that class formed from a single piece of wire, the object of my device being to provide a simple construction of clothes pin peculiarly bent in such a manner as to form clamping members by means of which articles of clothing or the like may be secured on a line in the usual manner.

Another object of my invention is the provision of a bracing means upon one of the clamping members for the coil, said means also serving to facilitate the application of the pin to a clothes line.

A further object of my invention is the provision of means formed upon one of the clamping members for holding the other clamping member in position.

Other objects as well as the nature and characteristic features and scope of my invention will be more readily understood from the following description taken in connection with the accompanying drawings and pointed out in the claim.

In the drawings: Figure 1, represents a side elevational view of my invention. Fig. 2, represents a front elevational view of my invention. Fig. 3, represents a transverse sectional view of my invention taken on line 3—3 of Fig. 1. Fig. 4, represents a transverse sectional view of my invention taken on line 4—4 of Fig. 1.

Referring more particularly to the drawings in which similar reference numerals designate corresponding parts throughout the different views, the numeral 1, represents a single piece of wire bent upon itself to provide a coil 2, and has a portion 3 thereof extending downwardly from said coil and bent upon itself as shown at 4, to form a duplex clamping arm or member 5—6. The extreme lower end of the duplex clamping arm 5—6 is bent slightly outwardly to provide a guide 7. Adjacent the guide 7, I have pressed the members of the duplex arm 5—6 inwardly together as at 8 and 9, for the purpose hereinafter described. The portion 6 of the duplicate clamping arm 5—6 is bent at right angles so as to extend

across the coil, the extreme terminal being looped as at 11 and engaged upon the coil 2 to bind the two strands of the coil together for limiting the movement of the coil and at the same time to constitute a stop for facilitating the application of the pin to a clothes line. The members of the duplex clamping arm 5—6 are bent outwardly intermediate their length to provide a pair of line clamping portions 12 and 13.

A portion 14, of the wire 1, extends downwardly from the coil 2, from the side opposite portion 3, to form a single clamping arm 15, which is bent at right angles as at 16, and extends between the members of the duplex clamping arm 5—6 as clearly shown in Figs. 1 and 2. The single clamping arm 15 is now bent downwardly and has a portion adjacent its lower end bearing 17 against the portions 8 and 9, of the duplex clamping arm 5—6, which prevents the single arm 15 from passing between the members of the same. The arm 15, is arranged outwardly opposite the outwardly bent portions 12 and 13, of the duplex member 5—6 to form a line clamping portion 17 which line clamping portions of the arms 5—6 and 15 are arranged in a substantially circular form. The outer end of arm 15, is turned outwardly in a direction opposite to that of the outturned end of the duplex clamping arm 5—6 to provide a guide 19 for the pin and has a loop or finger piece 20, arranged upon its extreme outer end. The outturned ends of the clamping members prevent the tearing of the clothes while the pin is being attached.

In attaching clothes to a line, the pin is grasped so that the thumb bears against 95 the loop 11 which incidentally is arranged at right angles to the finger engaging portion 14, the index finger on the same hand also engaging the portion 14 at the bend 15, as illustrated in Fig. 1 of the accompanying drawings. By arranging the guides 7 and 20 about the line with clothes thereon and by pulling downwardly on the pin, the clamping arms are forced away from each other until the line engaging portions 13 and 17 are arranged about the line. It is thought to be obvious that the spring action of the coil has a tendency to draw the arms together and securely fastening the article upon the line. In order to release an article all that is necessary to do is to grip the pin upon the portions 5—6 and 14, press

lightly upon the same and lift the pin, this pressure on the arms consequently causes the line engaging portions to swing away from each other.

5 This arrangement is particularly adapted in use for persons of short stature. Extreme difficulty heretofore experienced in applying clothes pins is easily obviated by the employment of applicant's arrangement.

10 The particular arrangement of the loop 11 which constitutes a stop, and this element's peculiar coöperation with the angularly bent portion 15 provides an efficient clothes pin.

15 It will be obvious to those skilled in the art to which this invention relates, modifications may be made in detail without departing from the spirit or scope of the invention.

Having thus described my invention, what 20 I desire to secure by Letters Patent is:

A device of the character described including a single piece of wire bent upon itself to provide a coil, a duplex clamping member depending from one side of said

coil, said member being formed by a portion of the wire being bent upon itself providing arms, the upper extremity of said duplex clamping member being bent at right angles so as to extend across the coil, a loop formed on the terminal of the duplex clamping member and engaged on the opposite side of the coil for binding the two strands of the coil together, a single clamping member bent at right angles from the body portion thereof and extending between the arms of the duplex member, said single clamping member being bent at right angles and having the lower end thereof bearing against said duplex clamping member, and said loop further constituting a 40 stop for the thumb of the user when applying the pin to a clothes line.

In testimony whereof I affix my signature in presence of two witnesses.

THOMAS F. BUDGE.
